GESELLSCHAFT, OF ESSEN-ON-THE-RUHR, GERMANY.

SAFETY DEVICE FOR FUSES FOR PROJECTILES.

1,372,582.

Specification of Letters Patent. Patented Mar. 22, 1921.

Application filed September 3, 1920. Serial No. 408,094.

To all whom it may concern:

Be it known that I, KARL WIESER, residing at Werden, Ruhr, Germany, a citizen of the German Republic, have invented a certain new and useful Improvement in Safety Devices for Fuses for Projectiles, of which the following is a specification.

This invention relates to a safety device for fuses for projectiles. The object of the invention consists in the prevention of premature explosion by means of a packing disk inserted in the ignition passage of the fuse during transport and capable of being thrown out of operation when required. According to the invention the packing disk is so disposed that the jet of flame resulting from premature ignition will bring about a bulging of the disk in the ignition passage and effect the required packing action which in comparison with known safety devices has the advantage that a gas-tight packing is secured in a simple way.

The invention will be further described with reference to the accompanying drawings which show as an example a percussion fuse with a packing disk according to the invention applied thereto and in which—

Figure 1 is a longitudinal section of the fuse,
30 Fig. 2 is a sectional plan on the line 2—2 of Fig. 1,

Fig. 3 is a side elevation, partially in section similar to Fig. 1, of the fuse after a premature ignition of the detonator has 35 taken place, and

Fig. 4 shows on a larger scale a side elevation, partly in section, taken approximately at right angles to the section shown in Fig. 1.

40 A denotes the body of the fuse, a^1 the firing pin, B the striker which carries the detonator b^1 and C is the bursting charge. The striker is prevented from premature movement toward the firing pin a^1 in the well known way by a centrifugal force 45 safety device D. From the detonator of the striker B, a passage formed by three interconnected passages b^2 , a^2 , a^3 leads to the bursting charge C. Between the passages a^2 and a^3 is inserted an irregularly shaped disk E which is pivotally mounted in the body 50 of the fuse, in such a way, that when the fuse is in the transport state this disk completely covers the passage a^3 . The apparatus is at the same time so constructed that

the disk is able to swing outward under the action of centrifugal force in the direction of the arrow x (see Fig. 2) and expose the passage a^3 . When the fuse is in the transport state the disk E is prevented from 60 swinging outward in the direction of the arrow x by a pin F (see Fig. 2), which when the gun is fired can fly back and thereby move out of the path of the disk E (see Fig. 4). To prevent the disk E from swinging 65 outward in the opposite direction to that indicated by the arrow x , which might happen when the gun was fired, under the action of inertia, a fixed pin a^4 is provided which bears against the disk E (see Fig. 2). 70 The thickness of the disk E and its material are so selected that when ignition of the detonator b^1 takes place before the disk E has swung outward the jet of flame resulting from such ignition causes a bulging of 75 the disk E into the ignition passage so that, as shown in Fig. 3, the passage a^3 is closed up perfectly tight and the jet of flame cannot consequently reach the bursting charge C. 80

Since disk E is pressed against the part of the igniter body surrounding the passage a^3 , with great force, at the beginning of the movement of the projectile, by the axial forces of inertia, and furthermore, the forces 85 of inertia produced by the rotary acceleration of the projectile tend to turn the disk in the direction opposite that of arrow x , an outward movement or oscillation of the disk under the action of centrifugal force 90 may thus first occur in the direction of the arrow x , when the projectile no longer receives an acceleration, i. e. when it has already left the barrel. The occurrence of a premature burst in the barrel is therefore 95 completely eliminated.

Claims:

1. A safety device for projectile fuses with a percussion pellet and an ignition passage which comprises a thin packing disk 100 normally covering said ignition passage, means for mounting said disk to enable it to be thrown out of operation transversely to the direction of the ignition passage, said packing disk being deformable by the jet 105 of flame resulting from the ignition of the percussion pellet to thereby bulge the disk into the ignition passage.

2. A fuse for projectiles which comprises a striker, a percussion pellet, an ignition 110

passage, a thin disk deformable by the jet of flame resulting from the ignition of the percussion pellet disposed across the ignition passage, means pivotally supporting said disk at one edge thereof, displaceable means for retaining the disk in its operative position, said disk being so mounted as to enable it to be thrown out of operation

transversely to the direction of the ignition passage.

The foregoing specification signed at Essen, Germany, this 19th day of June, 1920.

KARL WIESER.
